J. E. ERCANBRACK

HEAT TRANSFER DEVICE

Filed Aug. 9, 1926

Witness:
Chas. R. Lourds.

John Edward Ercanbrack
per Benj. J. Roodhouse, Atty.

UNITED STATES PATENT OFFICE.

JOHN EDWARD ERICANBRACK, OF CHICAGO, ILLINOIS.

HEAT-TRANSFER DEVICE.

Application filed August 9, 1926. Serial No. 128,187.

My present invention relates to heat transfer devices and has for its object the improvement in the efficiency thereof, which I accomplish by providing facilities for increasing and controlling the circulation of the fluid to be heated.

In heat transfer devices in general, where there may be some heat transferred by radiation, the greater part thereof is effected through conduction, that is, from the heating fluid to the walls of its container, through the walls of its container, and from the walls of its container to the fluid to be heated which is in contact with the said walls. It is therefore obvious that if a circulation of the heated fluid can be controlled and accelerated so as to bring a greater amount of fluid in contact with the walls of the container of the heating fluid the efficiency of the apparatus will be increased. Where no such accelerating and controlling means are provided the heated fluid, which rises upon being heated, mixes and eddies with the fluid through which it rises, thereby delaying circulation. This mixing and eddying of the heated fluid with the unheated, or the less heated, fluid also tends to decrease the temperature of the fluid rising from the container through which the heating material is circulated with the result that a greater proportion of fluid in the tank has to be heated before really hot fluid can be drawn therefrom. Whereas, as will hereafter be seen, my invention accumulates the hottest fluid in the top of the device where it can be drawn off for use at a higher temperature than could heretofore be secured until the entire, or a large portion of the fluid in the apparatus was brought to a desired heated condition.

I secure the foregoing objects and results by means of the structure illustrated in the accompanying drawings, in which—

Fig. 1 is a vertical, central, longitudinal section on the line 1—1 of Fig. 2 through a fragment of a heating tank or device in which my invention is embodied.

Fig. 2 is a section on line 2—2 of Fig. 1.

Fig. 3 is a section on line 3—3 of Fig. 1.

Fig. 4 is a section on the line 4—4 of Fig. 1.

Similar reference characters are employed for designating similar parts throughout the several views.

My present heat transfer unit consists of a tank 5, which I have shown as of the ordinary horizontal storage variety, provided in the lower part of an end wall 6 of which is an aperture 7. Suitably secured over the aperture 7 by bolts 8, or in any other suitable way, is a hollow boss 9, terminating in a flange 10. Extending through the boss 9 and into the tank 5 through the aperture 7 are a series of tubes 11, turned or bent intermediate their ends and terminating in a tube plate 12, which registers with the flange 10 and is separated therefrom by a preferably soft metal gasket 13. Another soft metal annular gasket 14 contacts the periphery of the front of the tube plate 12, and fitting against the gasket 14 is an exterior head 15 divided by a horizontal plate 16 into an upper compartment 17 and a lower compartment 18. The head 15, gaskets 13 and 14, tube plate 12 and flange 10 are secured together by bolts 19, and the front of the head 15 is tapped and threaded for connection with an inlet pipe 20 and an outlet pipe 21 leading to and from, respectively, the compartments 17 and 18. Arising from adjacent the bottom of the tank where they are secured by brackets 22 are two baffle plates 23 and 24, the lower portions of which are relatively close to the exterior rows of the tubes 11, and which are bent inwardly above the tubes 11 or shouldered at 25 to bring them somewhat closer together. From the inner bend of the shoulder 25 the baffles are extended vertically to adjacent the top of the tank 5 where each of them is turned centerwards as at 26 and carried downwardly again in lengths 23^a and 24^a to adjacent the top of the tubes 11. The vertical edges of the sheets 23 and 23^a and 24 and 24^a, respectively, are brought together as shown in Fig. 3 and between these compressed ends are riveted preferably square spacing and supporting bars 27, the upper ends whereof are bent and riveted as at 28 to the top of the tank 5. The tank 5 is further provided with tapped embossments 29 and 30 upon its top and like tapped embossments 31 and 32 upon its bottom. I have shown the embossments 32 and 29 provided respectively with an inlet pipe 33 and a discharge pipe 34 by means of which the tank 5 may be supplied with fluid to be heated and from which the heated fluid may be withdrawn or dis-

charged. The tapped embossments 30 and 31 are shown closed by plugs and are for clean out purposes, or for making other desired connections with the tank.

5 The operation of my device is as follows:

Hot water or steam, or other desired heating fluid, is introduced through the inlet pipe 20 to the tubes 11 from which it escapes or is discharged through the pipe 21. When 10 the fluid to be heated surrounding the tubes 11 in the tank 5 commences to heat, there is first liberated the air which the relatively cold fluid contains. This air rises against the inner faces of the baffles 23 and 24 and 15 collects in the compartments formed between the plates 23 and 23^a and 24 and 24^a respectively, until these compartments are filled with air when any excess goes up between the plates 23^a and 24^a to the discharge pipe 34 20 through which the air leaves the apparatus.

The fluid heated by contact with the tubes 11 rises between the plates 23^a and 24^a and is replaced by the unheated, or less heated, fluid from the tank flowing beneath the 25 baffles 23 and 24. The air collected between the plates 23 and 23^a and 24 and 24^a helps to insulate the heated column or stream of fluid rising between plates 23^a and 24^a from the fluid exterior of the plates 23 and 24 so 30 that the fluid reaches the top of the tank and about the juncture with the discharge pipe 34 with a higher temperature than it otherwise would have.

It will be seen that baffles without the air 35 compartments would prevent the mixing and eddying of the heated stream with the unheated, or less heated, circumambient fluid and thereby accelerate the circulation through and from the heating tubes 11, but 40 by providing the insulating air pockets, I am further preventing the conduction and loss of heat from the upwardly flowing heated fluid through the walls of the baffles to the surrounding or unheated, or less heated, 45 fluid so that the gravitational circulation of the fluid in the tank is directed and accelerated and the unheated, or less heated, fluid displaces the heated fluid in contact with the heating tubes without interference between these upwardly and downwardly flowing 50 bodies of fluid, and there is also immediately provided at the top of the tank where the discharge port is located and available for immediate withdrawal, a supply of fluid 55 which has not been robbed of the heat re-

ceived from the heating element through mixture with the surrounding fluid.

Having described my invention, what I claim as new, and desire to secure by Letters Patent is—

60 1. A heat transfer device comprising a tank for the fluid to be heated having inlet and discharge ports therein, the latter port being located in the top of said tank, a heating element consisting of conductors comprising a portion of a closed circuit for the conduction of a heat liberating medium, located within and adjacent the bottom of said tank, and baffles spaced from the bottom of said tank adjacent the sides of said heating element and extended upwardly therefrom to adjacent the top of said tank.

65 2. A heat transfer device comprising a tank for the fluid to be heated having inlet and discharge ports therein, the latter port being located in the top of said tank, a heating element located within and adjacent the bottom of said tank, and baffles spaced from the bottom of said tank adjacent the sides of said heating element and extended upwardly 70 therefrom to adjacent the top of said tank, said baffles being extended inwardly and then downwardly to form spaced air pockets opening above said heating element.

75 3. A heat transfer device comprising a tank for the fluid to be heated having inlet and discharge ports therein, the latter port being located in the top of said tank, a heating element located within and adjacent the bottom of said tank, and baffles spaced from the bottom of said tank adjacent the sides of said heating element and extended upwardly 80 therefrom to adjacent the top of said tank, said baffles being provided with heat insulating means operative to prevent conduction of heat between the fluid arising between said baffles and the fluid exterior thereof.

85 4. A heat transfer device comprising a tank for the fluid to be heated having inlet and discharge ports therein, means for imparting heat to the fluid within and adjacent the bottom of said tank comprising conductors arranged horizontally for the conduction of a heat liberating medium through 90 said tank and baffles surrounding the heating area and extending from adjacent the bottom to adjacent the top of said tank.

JOHN EDWARD ERCANBRACK.
